Primary Examiner — Rachel A. Voorhies(57) **CLAIM**

The ornamental design for a display screen with a graphical user interface, as shown and described.

DESCRIPTION

FIG. 1 is a front view of a display screen with a graphical user interface showing a first embodiment of our new design;

FIG. 2 is a front view of a display screen with a graphical user interface showing a second embodiment of our new design;

FIG. 3 is a front view of the second embodiment in a different environment;

FIG. 4 is a front view of a display screen with a graphical user interface showing a third embodiment of our new design; and,

FIG. 5 is a front view of the third embodiment in a different environment.

The dot-dash-dot broken lines show the display screen and form no part of the claimed design. The evenly broken lines illustrate portions of the graphical user interface that forms no part of the claimed design.
